ADJUSTABLE AIR DISTRIBUTOR

Otto A. Labus, La Crosse, Wis., assignor to The
Trane Company, La Crosse, Wis.

Application January 3, 1950, Serial No. 136,567

5 Claims. (Cl. 98—40)

1

This invention relates to a distributor for a stream of moving air or gas, and it is particularly adapted for mounting on a unit heater or on a duct outlet from which conditioned air or gas is flowing.

An object of the invention is to provide a distributor which may be adjusted to vary the amount of deflection of an air or gas stream.

Another object of the invention is to provide a distributor which may be adjusted to give different angles of deflection of the air or gas at different points around the axis of the air or gas stream and thus control the cross-sectional shape of the discharged stream and the general direction of discharge.

Another object of the invention is to provide a distributor which is particularly adapted for use in a fluid stream flowing from a propeller fan, because it changes the normal spiral movement of the stream into a substantially straight line flow and in this way increases the distance that the fan throws the fluid.

Another object of this invention is to provide a distributor having vanes in which the longitudinal geometric axes of the vanes lie on the surface of a cone having one angle when adjusted for maximum deflection of the air, and in which the longitudinal geometric axes of the vanes lie in a cone having a greater angle when adjusted for minimum deflection and maximum distance of throw of the air.

Another object of the invention is to provide a distributor which is simple and inexpensive to manufacture and which is adjustable to give good air distribution under different operating conditions.

Further objects of the invention will become apparent from the following specification taken in connection with the drawings which form part of this application, and in which:

Fig. 1 is a sectional view taken on line 1—1 of Fig. 2 showing the distributor of this invention applied to a unit heater.

Fig. 2 is a bottom view of the distributor as applied to a unit heater.

Fig. 3 is a sectional view taken on line 3—3 of Fig. 4 and showing a modification of my invention applied to an outlet of a duct or plenum.

Fig. 4 is a bottom view of the distributor of Fig. 3.

Referring now to the drawings, the distributor of the present invention is shown attached to a unit heater indicated generally by numeral 10. The unit heater 10 has an annular heating element 12 comprising a plurality of fluid conduct-

2

ing tubes 14 having heat conducting fins 16 thereon. A fan 18 is secured to the shaft of an electric motor 20 and is rotatably driven by said motor. Any well known prime mover can be used instead of the electric motor 20 if desired. The fan 18 draws air radially inwardly through the heating element 12 and forces the air downwardly through a discharge opening defined by the annular flange 22.

10 The unit heater 10 has supports 24 by which the unit is adapted to be supported above the breathing space of a room or other enclosure.

15 A generally frusto-conical member 26 has a rolled outer edge 28 for the sake of appearance and to provide stiffness. Four bent rods 30 support the conical member 26 from the annular flange 22 of the unit heater 10. The rods 30 have threaded holes at each end which receive screws 32 to fasten the rods 30 to the annular flange 22 and screws 34 to fasten the rods 30 to the conical member 26. It should be understood that the invention is not limited to the use of four rods. For instance three or even five rods could be used.

20 Conical member 26 has at its inner edge an upwardly extending right annular flange 36. A central hub 38 has a frusto conical portion 40 which perpendicularly intersects the surface of the cone in which the conical member 26 lies.

25 Air turning vanes 42 are pivoted at their outer ends on the flange 36 of conical member 26, and at their inner ends on the frusto conical portion 40 of the central hub 38. The vanes 42 may be pivoted to a fully open position in which they lie in planes which are radial to the axis of the distributor. This adjustment of the vanes is shown in the left side of Figs. 1 and 2. The vanes 42 may also be adjusted to a fully closed position in which they overlap and lie in substantially the same conical surface as the frusto conical member 26. This adjustment of the vanes 42 is shown in the right side of Figs. 1 and 2. The vanes 42 may be adjusted to any intermediate position between the fully open and the fully closed positions described above.

30 The vanes 42 are flat and they taper in width so that when adjusted to closed position there is a substantially uniform overlap along the length of the vanes. At each end near one longitudinal edge, each vane 42 has a perpendicular lug bent up from the blank from which the vane is made. One lug 44 of each vane abuts the flange 36 of frusto-conical member 26 and is pivotally secured thereto by a rivet 46. The other lug 48 of each vane abuts the frusto-conical portion 40 of the hub 38 and is pivotally secured thereto by a

rivet 50. The rivets 46 and 50 frictionally secure the vanes 42 to the frusto conical member 26 and the hub 38 so that the vanes will be held in their pivotally adjusted positions.

Figs. 3 and 4 show a modification of the distributor of my invention applied to the outlet flange 52 of a duct or plenum 54. According to this modification of my invention the parts are the same as those of Figs. 1 and 2 except that the rods 30 have been replaced by rods 56 and a generally frusto-conical member 58. The frusto-conical member 58 has an upwardly extending annular flange 60 which fits closely over the outlet flange 52. It should be understood that the flange 60 may be made to closely fit inside the outlet flange 52 if desired. The flange 60 is secured to the outlet flange 52 in any suitable manner as by screws, bolts or by welding. However I prefer to use screws 61 so that the distributor may be easily removed if desired. The frusto-conical member 58 has an upwardly extending flange 62 which joins the main portion of the member 58 on a substantial radius. A smooth outlet for the air stream is thus provided. The upwardly extending flange 62 functions to provide strength and rigidity to the frusto-conical member 58, and it also contributes to the appearance of the distributor. The rods 56 have threaded holes at each end to receive screws 64 to fasten the rods 56 to the frusto-conical member 58 and screws 66 to fasten the rods 56 to the frusto-conical member 26.

When the vanes 42 of my distributor are in fully closed position the air is caused to flow over the frusto-conical member 26 and the maximum angle of spread is imparted to the air stream. As the vanes are adjusted toward fully open position, more and more air flows between the vanes 42 and the angle of spread of the air stream is gradually reduced. I have found by tests of the distributor, when mounted on a unit heater as shown in Figs. 1 and 2, that the maximum distance of air throw and minimum angle of spread of the stream is obtained when the vanes are adjusted to an angle of about 10° from the vertical in the direction of rotation. It is significant that at this 10° vane setting, the distributor offers a negligible resistance to the flow of air with the result that the volume of air discharged is very nearly the same as that discharged by the fan when no distributor is used.

The vanes 42 of my invention have a pivotal axis substantially at the lower side edge of the vane for a reason that will now be explained. For the maximum desired spread of the air stream the vanes are fully closed and lie on the surface of a cone having a cone angle of about 120°. On the other hand when the vanes are adjusted to or near their fully open position, they are more effective when their longitudinal geometric axes lie on the surface of a cone having a cone angle greater than 120°. By pivoting the vanes at their lower side edges the cone angle of the geometric axes of the vanes increases from about 120° in closed position to about 135° in fully open position. It may also be pointed out that the lower longitudinal edges of the vanes remain in substantially the same angular positions for all pivotal adjustments of the vanes. In distributors of the prior art, vanes have been pivoted on their geometric axes. But this prior art construction has the disadvantage that the lower longitudinal edges of the vanes swing downwardly when adjusted toward fully open position with the result that the air is not effectively directed in the desired path.

Although I have described in detail the preferred embodiments of my invention, I contemplate that many changes may be made without departing from the scope or spirit of my invention, and I desire to be limited only by the claims.

I claim:

1. A distributor for directing the flow of an air stream flowing from an outlet comprising a frusto-conical annular air directing member adapted to be supported in spaced relationship to an outlet, a central hub, a plurality of vanes pivoted to said frusto-conical annular air directing member and to said central hub, the pivotal axes of said vanes lying substantially in the same conical surface as the frusto-conical annular air directing member.
2. A distributor for directing the flow of air from an outlet comprising a frusto-conical annular air directing member, support means secured to said frusto-conical annular air directing member and adapted to be secured to an outlet to support said frusto-conical annular air directing member in spaced relationship to the outlet, a central hub, a plurality of vanes, means pivotally mounting said vanes to said frusto-conical annular air directing member, means pivotally mounting said vanes to said central hub about axes which substantially coincide with the pivotal axes of the vanes with respect to said frusto-conical annular air directing member, the pivotal axes of said vanes lying substantially in the same conical surface as the frusto-conical annular air directing member.
3. A distributor for directing the flow of an air stream flowing from an outlet comprising, a frusto-conical annular air directing member, support means secured to said frusto-conical annular air directing member and adapted to be secured to an outlet to support said frusto-conical annular air directing member spaced from the outlet, a central hub, a plurality of elongated vanes extending between said frusto-conical annular air directing member and said central hub, means pivotally mounting said vanes to said frusto-conical annular air directing member and to said central hub about axes which lie substantially in the same conical surface as the frusto-conical annular air directing member, the pivotal axis of each vane substantially coinciding with the longitudinal vane edge which is farther removed from the outlet when the vane is in open position.
4. A distributor for directing the flow of a gas stream from an outlet comprising an annular frusto-conical gas directing member, means secured to said annular frusto-conical gas directing member and adapted to be secured to an outlet to support said annular frusto-conical gas directing member spaced from the outlet, a central hub, a plurality of elongated generally quadrilateral vanes, each of said elongated vanes being pivotally mounted at one end to said annular frusto-conical gas directing member and at the other end to said central hub on axes which lie substantially on a surface of a cone which diverges away from the outlet, said elongated vanes having longitudinal side edges which converge with respect to each other from said annular frusto-conical gas directing member toward said hub, the pivotal axis of each elongated vane substantially coinciding with the longitudinal elongated vane edge which is farther removed from the outlet when the elongated vanes are adjusted so that the elongated vanes

lie in planes which are radial to the axis of the cone, said elongated vanes being pivotally adjustable to a position in which the planes of the elongated vanes lie substantially in the same conical surface as the axes on which said elongated vanes are pivoted to direct the gas over said annular frusto-conical gas directing member.

5. A gas distributor adapted to be secured to an outlet to direct the flow of a gas stream from said outlet comprising an annular frusto-conical gas directing member, a central hub, a plurality of generally quadrilateral elongated vanes extending between said annular frusto-conical gas directing member and said central hub and having longitudinal edges which converge with respect to each other from said annular frusto-conical gas directing member toward said hub, means pivotally mounting said elongated vanes to said annular frusto-conical gas directing member and to said hub about axes which lie on the surface of a first cone, the pivotal axis of each elongated vane substantially coinciding with one longitudinal vane edge, said elongated

15 vanes overlapping each other in such a manner that each elongated vane is pivotally adjustable to a position in which the other longitudinal edge is nearer to the outlet than said one longitudinal edge whereby said other longitudinal edge is the entering vane edge with respect to flow, said elongated vanes being pivotally adjustable to a position in which the planes of the elongated vanes lie substantially in the surface of said first cone to direct the gas over said annular frusto-conical gas directing member.
